UNITED STATES PATENT OFFICE.

LOUIS STRICKEL, OF DETROIT, MICHIGAN, ASSIGNOR OF ONE-HALF TO
GEORGE C. WETHERBEE, OF SAME PLACE.

BRUSH-MACHINE.

SPECIFICATION forming part of Letters Patent No. 537,394, dated April 9, 1895.

Application filed April 23, 1894. Serial No. 508,749. (No model.)

To all whom it may concern:

Be it known that I, LOUIS STRICKEL, a citizen of the United States, residing at Detroit, county of Wayne, State of Michigan, have invented a certain new and useful Improvement 5 in Brush-Making Machines; and I declare the following to be a full, clear, and exact description of the same, such as will enable others skilled in the art to which it appertains to make and use the same, reference being had to the accompanying drawings, which form a part of this specification.

My invention has for its object an improved machine for the manufacture of brushes, 15 whereby their manufacture may be economized and simplified, the machine being intended to save labor and to accomplish the desired ends in a superior manner.

My improved machine is calculated and designed to force the stock into the brush head, to secure the stock in the head by suitable binders, to drive the nails required to hold the binders in place, to drive the ends of the binders into the brush head, to automatically form 25 as well as to drive the nails, and also to automatically form and drive the staples into the ends of the brush head to secure the ends of the stock in place.

My invention, therefore, consists in the general construction, combination and arrangement of the devices and appliances hereinafter specified and claimed, and illustrated in the accompanying drawings, in which—

Figure 1 is a side elevation illustrating my invention. Fig. 2 is a plan view. Fig. 3 is a front elevation. Fig. 4 is a detail view in front elevation showing features of the nail cutting and driving mechanism. Fig. 5 is a vertical section on the line 5—5, Fig. 4. Fig. 6 is a longitudinal vertical section on the line 6—6, Fig. 2, showing the machine in its inoperative or retracted condition. Fig. 7 is a detail view of one of the pitman connections 40 operating the staple mechanism. Fig. 8 is a vertical longitudinal section showing the parts of the machine in advanced or operative position. Fig. 9 is a detail view of one of the staple driver bars. Fig. 10 is a detail view in plan of the staple making and driving mechanism. Fig. 11 is a vertical section

on the line 11—11, Fig. 10. Fig. 12 is a detail view of the die plates for forming the staples. Fig. 13 is a detail view of the staple driver. Fig. 14 is a detail view showing one of the wire feeders. Fig. 15 is a view in perspective illustrating features of the wire feeding and nail driving mechanism. Fig. 16 is a detail end view of the tilting bar beneath the wire feeders. Fig. 17 is a rear elevation of the nail cutter and driver, shown in Fig. 4. Fig. 18 is a front elevation of the staple maker shown in plan in Fig. 10. Fig. 19 is a detail view of a brush made by my improved machine, the view of the brush being shown to more clearly illustrate what my improved machine is designed to accomplish.

To more fully explain the purpose of my machine, the numeral 1 indicates a brush head formed with longitudinal grooves 2, into which the stock 3 is forced in any suitable manner. 70 A longitudinally extended binder wire 4 is forced with the stock into the corresponding groove 2, the ends of the binder wire being bent, and, in the completed brush, driven into the ends of the brush head as indicated at 5. 75 Staples 6 are driven over the ends of the stock into the ends of the brush head to hold the stock in place, and nails 7 are driven over the binder wire into the brush head to effectually secure the binder and stock in place. To secure these results, my machine includes any suitable supporting frame A provided with a table A' upon which the brush head is engaged in advance of the nail driver block B, and against which the head is firmly held by 80 a movable head block C. The head block is conveniently operated by means of a lever C' fulcrumed to the table A', as shown at "c," the lever C' being operated by a treadle C². The upper end of the lever C' is preferably 85 forked, as shown at c' and c², adjusting screws C³ and C⁴ connecting the head block C with the extremities of the forks c' and c².

It will be evident that by placing the foot upon the treadle C² the head block C will be 90 forced firmly against the brush head to bind the brush head between the head block and the nail driver block B.

D represents a vertically reciprocatory carriage which, as shown, is constructed with 100

vertically movable uprights D' made reciprocatory in suitable ways "a," indicated in dotted lines, Fig. 3, in the supporting frame.

D² denotes a cross-bar located between the uprights D' and made vertically adjustable, as by adjusting screws D³ connecting the extremities of the cross-bar with the upper inwardly directed extremities "d" of the uprights D'. Upon this cross-bar D² is engaged the customary driving plate E by which the stock and the binder wire are forced into the brush head. To this end, the cross-bar may be provided with a supporting head L⁴ provided with a supporting pin d', the driving plate being constructed with an orifice to receive said pin. The descent of the vertical carriage D presses the stock into the brush head, and remains in such position, to hold the stock and the binder wire in place until the nails are driven over the binder wires to secure them in place.

F is the main driving shaft suitably journaled in the supporting frame A. While I do not limit myself to any particular driving mechanism, I have shown the driving shaft provided with a driving pulley F'.

G is a rotatable shaft journaled in the supporting frame A, provided with a gear G¹ meshing with a pinion F² of the driving shaft F.

F³ denotes a clutch of any suitable construction adapted to engage the pulley F'. As shown, the clutch is provided with a lever arm F⁴ connected by a pitman F⁵ with a treadle F⁶.

F⁷ is a retracting spring.

H denotes a horizontally reciprocatory carriage which may be formed with side bars H', a front cross head H² and a rear cross-bar H³.

H⁴ denotes oscillatory uprights connected respectively by connecting bars H⁵ with cross-bars H³ of the carriage H. The shaft G is provided with a cam G² provided with rollers "g" extended therefrom on either side, and arranged to bear upon the uprights H⁴, at a given stage in the operation of the apparatus, to press said uprights forward and thereby advance the carriage H. The lower extremities of the vertical side-bars D' of the carriage D are connected by a cross bar D⁵. With this cross bar D⁵ is connected a rearwardly extended lever "I" fulcrumed toward its forward end, as at I', the rear end of said lever resting upon the periphery of the cam G². The rear extremity of the lever "I" is weighted, as shown at I², to hold the carriage D normally in a raised position. As the cam rotates, the rear extremity of the lever "I" will be lifted, thereby forcing downward the carriage D. In this manner, both the vertical carriage D and the horizontal carriage H are operated by the cam G².

H⁶ denotes retracting springs to retract the carriage H. The cross head H² is provided with nail driving arms or fingers H⁷. Supported upon the side-bars H' of the carriage H, as upon brackets "h," is a feeder bar H⁸ provided with a suitable number of feeders

h', the bar H⁸ being rotatable in the brackets "h."

H⁹ is a guide plate through which the wire is led to form the staples and the nails, the wires h² being the wires from which the nails are made, and the wires h³ being the wires from which the staples are made. To advance the wire to the staple making and nail making mechanism, the feeders h' are arranged to grip the wire at the proper time when the carriage is advanced, and thereby advance the wire from the reels J. The shaft H⁸ being rotatable evidently permits the feeders to slide over the wire when the carriage H is retracted. The feeders h' are constructed with an edge at their lower ends to suitably grip the wire when in contact therewith as the carriage H is advancing.

The drivers H⁷ are made reciprocatory in suitable orifices "b" in the nail driver block B located in advance of the cross head H². The nail driver block B is also provided with suitable orifices b' through which the wire is fed.

B' denotes a suitable cutting blade made vertically reciprocatory within a suitable channel b² in the driver block B.

B² denotes a clamping plate made adjustable for holding the knife in position in said channel. Any desired adjustment of the plate B² may readily be effected by set screws b³ entering the front face of the driver block B. Instead of making the driver block B of an integral body, I prefer to construct it with an upper channeled block B³ engaged therewith, as by bolt b⁴. The plate B² and block B³ are formed with a series of elongated chambers b⁵, of a length suitable for a single nail. In the operation of cutting the nails, the wire h² is advanced through the orifices b' beneath the elevated cutter blade B', to the forward end of the corresponding chamber b⁵. The knife descending, cuts the wire, the nails dropping to the base of the chambers b⁵ in advance of the drivers H⁷. When said drivers are advanced in the orifices "b," the nails are driven thereby forward through the channels "b" into the head block. To operate the knife B', the knife is provided with a lever arm B⁴, fulcrumed upon a suitable standard B⁵ engaged upon the driver block B, as shown at b⁶. The carriage D is provided with a rearwardly extended arm d², arranged to strike the outer end of the lever arm B⁴ as the carriage D descends, thereby lifting the cutter. The cutter descends when the lever B⁴ is released from engagement with the arm d² and cuts the wire to make the nails. This operation of the cutter and the formation of the nails take place in advance of the forward movement of the carriage H, thus forming the nails in readiness for the forward movement of the drivers H⁷.

It is evident that the carriage H must advance and retract a suitable distance to drive the nails into the brush head and to withdraw the drivers H⁷ out of the way of the nail cut-

ter, while the wires h^2 must only be advanced the length of a single nail. Therefore, the carriage H must be advanced and retracted a considerable distance more than it is required to advance the wire at each operation. In consequence, the feeders h' must be arranged so as not to grip the wire until the carriage H has been suitably advanced, or advanced a considerable distance of its forward movement. To accomplish this result, I locate beneath the feeders a tilting bar K, eccentrically journaled in the brackets "h," as shown at "k," one of the eccentric journals being shown at k' , Fig. 16. Depending from the tilting bar K is a tilting arm K'. To tilt said bar K', I locate a forked bar K² which is made adjustable in a suitable bracket k^2 in the frame A as by an adjusting nut k^3 . The tilting bar K is preferably rounded at its front upper corner, as shown at k^4 . In its normal position the bar K lifts the feeders h' off the corresponding wires so that the carriage H may be advanced while the feeders are so lifted, without advancing the wire. At a suitable stage, however, in the advancement of the carriage H, the tilting arm K' strikes the forked bar K², in consequence of which, the bar K is tilted, and owing to its being eccentrically journaled permits the feeders h' to drop upon and grip the wires which are consequently advanced the remainder of the distance, through which the carriage H is moved forward. When the carriage is retracted, the bar K resumes its normal condition, lifting the feeders. In this manner as the carriage H is advanced, the nails are cut and driven. As the pulleys "g" and the cam G² ride out of engagement with the oscillatory bars H⁴, the carriage H is automatically retracted by means of the springs H⁶, ready for another advance movement.

I will now proceed to describe the staple making and driving mechanism.

Inasmuch as the staple making mechanism is duplicated on each side of the machine, it will only be necessary to describe the construction of one of them. Accordingly, L represents a staple block secured upon the bed or table A' of the supporting frame in any suitable manner. This block is constructed with a laterally extended groove L' in which is reciprocated a staple driver M. Above the driver M is located a staple making die plate N, formed with a suitable die "n" at its forward end. I prefer to form the groove L' in a piece of steel L², Fig. 18, set into the block L, inasmuch as said groove forms a guide for the reciprocation of the driver M. The driver is preferably formed towards its forward end with lateral flanges, as shown at "m," to engage the staple, the groove being of similar form in cross section, as indicated in Fig. 18. The block L is provided with a top plate L³ secured thereupon, formed with a socket L⁴ to receive the end of the customary brush clamp, not shown. The wire from which the staples are made is fed through a

suitable orifice, as at "l," transversely to the movement of the driver M. The plate L³ is constructed with an outwardly projecting die 70 l' of suitable form to permit the die plate N advancing thereabout to bend the staple, the staple falling when completed into the upper portion of the groove L', in position to be driven by the advancement of the driver M 75 into the end of the brush head. Beneath the socket L⁴ is a groove L⁵, shown most clearly in Figs. 10, 11, and 18, essentially of the same width as the base or body of the driver M, the groove L⁵ serving to receive the hook end of 80 the binder wire 5, shown in Fig. 19, located over the stock to retain the same in place. As the driver M advances, it both drives the staple and clinches the binder wire into the head of the brush in one operation. 85

To reciprocate the die plate N, I provide a bell crank lever P fulcrumed, as at P', upon the block L, the front end of said lever P engaging a stud N' upon the die plate N. With the opposite end of the lever P is engaged a 90 pitman Q, the forward portion of the pitman being provided with an elongated slot "q" engaging a spur or stud P² on the lever P. Upon the shaft G are located cams G³ and G⁴ to reciprocate the duplicate pitmen Q Q. 95 With the rear ends of the pitmen Q Q are engaged vertical oscillatory levers R and R', fulcrumed at their base, as shown at R², Fig. 1, the cams G³ and G⁴ bearing upon said levers R and R' respectively to force them forward, 100 said pitmen being retracted by springs R³ and R⁴. As the levers R and R' are thrown forward, the corresponding bell crank levers P are operated to advance the die plate N connected therewith. 105

I prefer to construct each pitman Q in two parts, as indicated more specifically in Fig. 7, to permit of the regulation or adjustment of the pitman as may be required. This may be accomplished by providing each part Q', 110 Q², with adjacent brackets q' and q², an adjusting screw Q³ being provided, whereby said brackets may be set at any given distance the one from the other, to lengthen or shorten the entire pitman Q. The arm or part Q² is 115 shown underlapping the part Q'. When the two parts have been properly adjusted, they may be united by suitable bolts q³.

To advance the driver M, I provide a horizontally oscillatory lever M' having a jointed engagement with the corresponding driver, as shown at m'. The rear extremity of the lever M' is beveled, as shown at m². Upon each of the side bars H' of the carriage H, is engaged a cam S, against the front face of which 120 bears the beveled rear face or end of the corresponding lever M'. It will readily be seen that as the carriage H advances, the levers M' and M' of the duplicate staple making mechanism, are spread apart at their rear 125 ends, throwing their forward ends inward to advance the corresponding driver M, each lever M' being fulcrumed intermediate its ends, 130 as shown at m³. A spring M² connecting the

rear extremities of the two levers M' , M' , retract the corresponding drivers when the carriage H retracts.

The parts of the machine are so adjusted 5 as to co-act in suitable succession. Thus, the staple making mechanism is first operated to form the staples. This is accomplished by the arrangement of the cams G^3 and G^4 to operate in advance of other parts of the machine, or in advance of the operation of the cam G^2 . After the two cams G^3 , G^4 , have operated the mechanism to make the staples, the cam G^2 operates to force downward the vertical carriage D , and then rollers "g" are 10 brought into contact with the vertical levers H^4 H^4 to force forward the carriage which operates the nail making and driving mechanism.

The several parts may be retracted in any 20 suitable manner within the scope of my invention.

The feeders h' are made laterally adjustable on the shaft H^8 for different sizes of brushes. The two bell crank levers P of the 25 duplicate staple making mechanism are turned in opposite directions upon the two sides of the machine, that shown in Fig. 10 being at the left hand of the machine.

The head-block H^2 is cut away on its upper face as shown in Fig. 15, at V , to allow 30 the carriage to feed the staple wire farther than the nail wire. It will be observed by reference to said figure that the orifices "v," through which the wires h^3 are fed are lower than the orifices v' through which the wires 35 h^2 are fed. This construction permits the corresponding feeders to grip the staple wires more quickly than the intermediate feeders grip the nail wires. The staple wire feeders, 40 it will be observed, are a little longer than the nail wire feeders. The staple wire is cut for the staples on the edges of the dies.

The hook l^4 shown in Fig. 11 attached to 45 the wall of the socket L^4 is to prevent the die plate N from withdrawing the staple in case it might be clamped or otherwise held fast in the orifice "n" of the staple plate N in its retreat.

The mode of making the brush is as follows: The head of the brush is held in place 50 between the nail driver block and the head block C . The stock and binder wire for a single groove are then forced into the brush head by means of the descent of the carriage 55 D and driving plate E . The nails are then driven over the binder wires and also the staples into the ends of the brush head by the mechanism hereinbefore described. The hook projects downward behind the staple and 60 strips it from the die when the die is retracted.

What I claim as my invention is—

1. In a brush making machine, the combination of a supporting frame, a device for 65 holding a brush head, a device for forcing the stock into the brush head, wire feeders, a cutter for severing the wire into nails, drivers

for driving the nails so formed into the brush head to retain the stock therein, devices for forming the wire into staples and for driving 70 the staples so formed into the ends of the brush head, and driving mechanism for the movable parts of the machine, substantially as set forth.

2. In a brush making machine, the combination of a horizontally sliding carriage, wire feeders and nail drivers carried by said carriage, an eccentrically journaled tilting bar K extending underneath said wire feeders to hold the wire feeders out of operation during 80 a portion of the forward movement of the carriage, and means to tilt the tilting bar at a given stage in the advancement of the carriage to force the wire feeders into contact with the wire, substantially as set forth. 85

3. In a brush making machine, the combination of a supporting frame provided with guide ways, a vertically reciprocatory carriage D mounted to slide in said guide ways, a lever engaged with said carriage, means to actuate 90 said lever to force the carriage downward, means to retract the carriage, a device for holding a brush head, and a driving device carried by said carriage to drive the stock into said brush head, substantially as set forth. 95

4. In a brush making machine, the combination of a supporting frame, a vertically reciprocatory carriage D provided with a vertically adjustable cross bar D^2 , a driving device carried by said cross bar to drive the 100 stock into said brush head, a horizontally reciprocatory carriage, vertically oscillatory levers H^4 connected with said carriage nail drivers and wire feeders carried by said horizontally reciprocatory carriage, and means to 105 sever the wire into nails, and driving mechanism for the movable parts of the machine substantially as set forth.

5. In a brush making machine, the combination with a supporting frame, a vertically reciprocatory carriage D , a driving device carried by said carriage to drive the stock into the brush head, wire feeders, and a cutter to sever the wire into nails, said cutter actuated by the reciprocation of said carriage, 115 substantially as set forth.

6. In a brush making machine, the combination of a supporting frame, a device for holding a brush head, wire feeders, dies for forming the wire into staples, means for actuating one of said dies, and a reciprocatory driver to drive the staples so formed into the end of the brush head, substantially as set forth. 120

7. In a brush making machine, the combination of a supporting frame, a device for holding a brush head, wire feeders, dies for forming the wire into staples, a reciprocatory driver to drive the staples so formed into the end of the brush head, a horizontally reciprocating pitman, and a bell crank lever connecting the pitman with one of said dies, substantially as set forth. 125

8. In a brush making machine, the combi-

- nation of a supporting frame, a device for holding a brush head, wire feeders, dies for forming the wire into staples, means for actuating one of said dies, a self-retracting driver 5 to drive the staples so formed into the end of the brush head, and a horizontally oscillatory lever connected with said driver to force it forward to drive the staples, substantially as set forth.
- 10 9. In a brush making machine, the combination of a supporting frame, a device for holding a brush head, a horizontally reciprocating carriage, wire feeders, dies to form the wire into staples, means for actuating one of 15 said dies, a driver to drive the staples so formed into the ends of the brush head, a horizontally oscillatory lever connected with said driver actuated by said carriage to force the driver forward to drive the staples, and means 20 to retract said lever, substantially as set forth.
10. In a brush making machine, the combination of a supporting frame, a device for holding a brush head, a horizontally reciprocating carriage provided with cams S, wire 25 feeders, dies to form the wire into staples at each end of the brush head, means for actuating the dies, drivers to drive the staples so formed into the ends of the brush head, horizontally oscillatory levers connected with said 30 drivers and actuated by said cams to force forward the drivers to drive the staples, and means to retract said levers, substantially as set forth.
11. In a brush making machine, the combination of a supporting frame, a driving device 35
- to force the stock and binder wire into the brush head, wire feeders, staple making mechanism to form the wire into staples, and reciprocating drivers to drive the staples so formed and the ends of said binder wire into the ends of the brush head, substantially as set forth. 40
12. In a brush making machine, the combination of a supporting frame, a device for holding a brush head, wire feeders, duplicate 45 sets of dies at each end of the brush head to form the wire into staples, duplicate drivers to drive the staples so formed and to clinch the ends of the binder wires of the brush head, and means for actuating the movable 50 parts of the staple making and driving mechanism, substantially as set forth.
13. In a brush making machine, the combination of a block L formed with a groove L', of die plates engaged with said block to form 55 a staple, a driver reciprocating in said groove to drive the staple, the staple falling into the groove L' in advance of the driver, substantially as set forth.
14. In a brush making machine, the combination of a block L formed with a groove L', of dies to form a staple, a driver reciprocating in said groove, and means to strip the staple from the dies, substantially as set forth. 60
- In testimony whereof I sign this specification in the presence of two witnesses. 65
- LOUIS STRICKEL.
